UNITED STATES PATENT OFFICE.

OTTO A. HOKANSON, OF WOODSTOCK, ILLINOIS, ASSIGNOR TO WOODSTOCK TYPE-WRITER COMPANY, OF WOODSTOCK, ILLINOIS, A CORPORATION OF ILLINOIS.

VARIABLE LINE SPACER.

Application filed August 13, 1921. Serial No. 492,135.

To all whom it may concern:

Be it known that I, OTTO A. HOKANSON, a citizen of the United States, residing at Woodstock, in the county of McHenry and 5 State of Illinois, have invented certain new and useful Improvements in Variable Line Spacers, of which the following is a specification.

This invention relates to mechanism for 10 rotating a typewriter platen for line spacing, including means for shifting the platen various amounts differing from the ordinary line spacing. The invention has for its object the provision of mechanism of the class 15 named which shall be of improved construction and operation. It is exemplified in the combination and arrangement of parts shown in the accompanying drawing and described in the following specification and 20 is more particularly pointed out in the appended claims.

In the drawings—

Fig. 1 is a fragmentary longitudinal section of a typewriter platen support showing 25 one embodiment of the present invention applied thereto;

Fig. 2 is a transverse section substantially on line 2—2 of Fig. 1;

Fig. 3 is a section on line 3—3 of Fig. 1; 30 Fig. 4 is a view similar to Fig. 2 showing a slightly modified form of the invention;

Fig. 5 is a section on line 5—5 of Fig. 4;

Fig. 6 is a view similar to Figs. 2 and 4 showing another modification; and 35

Fig. 7 is a section on line 7—7 of Fig. 6.

In Fig. 1 the numeral 8 designates a platen mounted on a platen shaft 9 which is provided with a milled groove, as shown at 10. A sleeve 11 surrounds the shaft 9 and is 40 provided with an extension 12 to which the platen 8 is secured by a set screw 13. A second sleeve 14 is detachably secured to the sleeve 11 by a set screw 15. The sleeve 14 is detachably fixed to the shaft 9 by a set screw 45 16. The sleeve 11 is journaled in the platen carriage frame 17 and is held in place by the sleeve 14. A knob or finger piece 18 is molded or otherwise fixed on the end of the sleeve 14. It will be apparent that rotation 50 of the knob 18 will rotate the platen 8 in the usual manner.

A housing 19 is rotatably journaled on an enlarged portion 20 of the sleeve 11 and a ratchet wheel 21 is fixed to the housing 19 55 to rotate therewith. A disc 22 is formed

on the end of the enlarged bearing portion 20 of the sleeve 11 and has opposite edges thereof flattened to form straight runways, as shown at 23 in Fig. 2. The housing 19 is provided with an overhanging flange or 60 ring 24 which engages the outer periphery of the disc 22. A plurality of dogs 25 are pivotally secured upon the face of the disc 22 by screws 26. The dogs are arranged in pairs, as shown in Fig. 2, the dogs of 65 each pair being provided with rollers 27 which extend into the opening adjacent the runways 23. Coil springs 28 normally press the rollers 27 away from one another and into the bights between the runways 23 and 70 the inner surface of the flange 24. It will be apparent that the rollers 27 will thus form a clutch or lock for holding the housing 19 against rotation relative to the disc 22. Any usual line spacing mechanism is 75 provided for rotating the ratchet wheel 21, and this rotation will be transmitted through the housing 19 and disc 22 to the platen shaft 9.

It is sometimes desirable to rotate the 80 platen independently of the ratchet wheel 21 for adjusting the spacing of the paper relative to the printing line or for other purposes. In order that this may be done, mechanism is provided for releasing the 85 clutch rollers 27 to permit the platen to be rotated while the ratchet wheel 21 remains stationary. The releasing mechanism for the clutch rollers 27 comprises a lever plate 29 journaled on the projecting flange 12 on the disc 22. A rod 31 is centrally positioned in the platen shaft 9 and is provided with an angularly bent end 32 positioned in a notch 33 in the lever plate 29 so that rotation of the rod 31 turns the lever plate in unison 90 therewith. The milled slot 10 in the shaft 9 is flared outwardly to permit a slight rotation of the rod 31 relative to the shaft, and the flange 12 is cut away in a similar manner. The lever plate 29 is provided with fingers 34 which extend between tailpieces 35 on the dogs 25. The lever plate 29 is also provided with shoulders 36 positioned adjacent the tailpieces 35. Rotation of the rod 31 in either direction will cause the 95 notches between the fingers 34 and the shoulders 36 to engage the tailpieces 35 and simultaneously swing all of the tailpieces outwardly, thus moving the rollers 27 toward one another against the tension of the 100 105 110

springs 28. This movement will release the rollers 27 to permit relative rotation between the platen and the ratchet wheel 21.

The rod 31 extends beyond the end of the sleeve 14 and is provided with a knob 37 secured to its outer end and having a flange 38 journaled on the end of the sleeve 14. The flange 38 recessed, as shown at 39, and an open spring ring 40 is housed in the recess. As shown in Figs. 1 and 3, the ring 40 has its ends slit forming tongues 41 and 42 which are oppositely bent, the tongues 41 engaging the sides of a slot 43 in the outer wall of the recess 39, and the tongues 42 engaging the walls of a slot 44 in the end of sleeve 14. As will be seen from Fig. 3, the ring 40 will resiliently hold the two slots 43 and 44 in alinement with the bent end 32 of the rod 31 in central position shown in Fig. 2. The knob 37 may be rotated a limited amount in either direction relative to the sleeve 14 to move the bent end 32, but when the knob is released it will be automatically returned to central position by the spring ring 40.

When it is desired to adjust the platen 8 relative to the ratchet wheel 21 it is only necessary for the operator to grasp the knob 37 and turn the knob in the direction in which the platen is to be rotated. The first effect of the rotation of the knob 37 will be to move the lever plate 29 a sufficient amount to release the rollers 27. Further rotation of the knob will bring the tongues 41 and 42 into engagement with one another and at the same time bring the end 32 of the rod 31 against the face of the groove 10 in the shaft 9. As the knob continues to rotate the tongues 41 and 42 and the bent end 32 of the rod 31 will tend to rotate the platen shaft and adjust the platen any amount desired by the operator. The adjustment of the platen may be effected equally well in either direction relative to the ratchet wheel 21. The platen may be rotated by the knob 18 under control of ratchet wheel 21 in the usual manner, or the knob 18 may be omitted and rotation of the platen under control of the ratchet may be performed by a knob at the other end of the platen.

In the form of the invention shown in Figs. 4 and 5 the mechanism is similar to that described, except that the tailpieces 35 on the dogs 25 bear against opposite edges of blocks 45 pivotally held by screws 46 on the face of the disc 22. The inner ends of the blocks 42 are notched at 47 to receive tongues 48 on the lever plate 29. Rotation of the rod 31 will swing the blocks 45 about their pivots and operate the dogs to release the clutch rollers. The other operation of this form of the invention is similar to that previously described.

In the form of the invention shown in

Figs. 6 and 7 the opposite edges of the disc 22 are cut away along curves 23, as shown in Fig. 6, the curves 23 being preferably arcs of circles of comparatively long radii. This provides bearing surfaces for the rollers 27 which insures positive action of the clutch rollers without jamming or sticking. In this form of the invention the rollers 27 are carried by dogs 49 having tailpieces 50 arranged to bear against tongues 51 on the lever plate 52. The plate 52 is mounted on the flange 12 and operated by the bent end 32 of the rod 31 in the manner previously described. It will be seen that movement of the lever plate 52 in either direction will cause the tongues 51 to release diagonally opposite rollers 27, but will not affect the remaining rollers. However, continued rotation of the shaft 9 in the direction of the releasing movement of the lever plate 52 will draw the remaining rollers 27 in a direction to release them from their clutching action so that a positive releasing movement of these rollers is unnecessary. The lever plate 52 is provided with a slot 53 through which a screw 54 passes to hold the lever plate in position on the disc 22. The operation of this form of invention in other respects is similar to that previously described.

I claim:

1. The combination with a platen and a line spacing wheel loosely mounted thereon, of a clutch disc connected with one of said members, a clutch ring connected with the other of said members and surrounding said disc, said disc having a portion of the periphery thereof flattened to provide a clutching surface inclined to the surface of said ring, a pair of oppositely disposed clutching rollers positioned in the space between said flattened surface and said ring, resilient means for forcing said rollers in opposite directions into the bights between said disc and ring, pivot levers for shifting said dogs toward one another against the tension of said ring, and means for simultaneously operating said levers to release both of said rollers.

2. The combination with a platen and a line spacing wheel loosely mounted thereon, of a clutch disc connected with one of said members, a clutch ring connected with the other of said members and surrounding said disc, said disc having opposite portions thereof flattened to provide clutching surfaces, a pair of oppositely acting rollers arranged to travel on each of said clutching surfaces, resilient means for forcing said rollers into clutching position, pivot levers for moving said rollers out of clutching position, a finger wheel connected with said platen, and means actuated by said finger wheel when rotated in either direction for simultaneously actuating all of said levers for releasing said clutch rollers.

3. The combination with a platen and a line-spacing wheel loosely connected therewith, of a pair of oppositely acting clutch rollers for holding said platen in fixed relation with said line-spacing wheel, said clutch rollers being positioned at opposite ends of the lunate opening between two curved surfaces of different radii with which surfaces they cooperate to hold said wheel and platen in fixed relation to one another.
4. The combination with a platen and a line-spacing wheel loosely connected therewith, of clutch members connected respectively with said wheel and platen, said clutching members having curved surfaces arranged to converge toward one another and providing a lunate opening therebetween, a pair of rollers positioned between said surfaces one at each end of said lunate opening and arranged to cooperate therewith to hold said platen and wheel in fixed relation to one another, levers connected with said rollers, and a rotary member arranged to actuate one of said levers at the beginning of rotation thereof.
5. The combination with a platen and a line-spacing wheel rotatably mounted on the axis thereof, a pair of clutch members connected respectively with said wheel and platen, said clutch members having oppositely disposed and differently curved clutch surfaces which converge toward one another, rollers interposed between said surfaces, resilient means for pressing said rollers into the bights between said surfaces to hold said platen and line-spacing wheel in fixed relation to one another, a lever for releasing one of said rollers to permit rotation of said wheel and platen relative to one another, a rotary member for actuating said lever during the beginning of rotation thereof, and a spring interposed between said rotary member and said platen.
6. The combination with a platen, of a line spacing wheel loosely mounted thereon, cooperating clutch members connected with said platen and wheel respectively, clutch rollers interposed between said clutch members, a rotary finger-piece for releasing said clutch rollers, said finger-piece having limited movement relative to said platen, and a spring for resisting relative movement of said finger-piece and platen, said spring being arranged to return said finger-piece to its normal position relative to said platen after rotation thereof.
7. The combination with a platen, of a line spacing wheel loosely mounted thereon, clutch mechanism for holding said platen and wheel in fixed relation to one another, means for releasing said clutch mechanism, a rotary finger-piece for actuating said releasing means, opposed abutments connected with said finger-piece and platen, and a spring interposed between said abutments for resisting relative movement thereof in either direction and for returning said finger-piece to its normal position relative to said platen after rotation thereof.

In testimony whereof I have signed my name to this specification on this 4th day of August, A. D. 1921.

OTTO A. HOKANSON.
